HIGHCHAIR OR THE LIKE

Robert D. Gunnell, 7768 Waterman Road,
Vassar, Mich. 48768

Filed Nov. 1, 1965, Ser. No. 87,959

Term of patent 14 years

(Cl. D15—1)

FIG. 1

FIG. 2

FIG. 3

FIG. 4

FIG. 5

FIG. 6

The dominant characteristics of my design are shown in full lines in the drawings.

I claim:

The ornamental design for a highchair or the like, as shown and described.
